CAN CARRIERS

Patrick A. Toensmeier, Hamden, Conn., assignor to The New Haven Board & Carton Company, New Haven, Conn., a corporation of Connecticut

Application May 4, 1956, Serial No. 582,790

6 Claims. (Cl. 229—40)

This invention relates to cartons for holding a plurality of like articles and is concerned more particularly with a novel carton or carrier for use in the shipment, display, and transportation of a plurality of cans having chimes at at least one end, such as those used for beer, scouring powders, etc. The new carrier includes means for engaging the chimes of the cans to retain the cans in the carrier and the carrier is similar to but an improvement upon the carrier shown in my Patent No. 2,678,767, issued May 18, 1954.

The carrier of the patent has the form of a sleeve made up of side walls connected by top and bottom walls and the sleeve is of a size to hold a plurality of cans in a row with the walls fitting snugly against the sides and tops and bottoms of the cans. The end cans in the row are held in the sleeve by retaining flaps cut from the top and bottom walls of the sleeve and connected to the walls along fold lines, from which the flaps project inwardly toward the middle of the walls. The retaining flaps are bent out of the plane of their walls and extend into the interior of the sleeve to engage the inner surfaces of the can chimes and the flaps are held in effective position by holding flaps attached to the top and bottom walls of the sleeve along fold lines lying outwardly from retaining flap fold lines. In the erected carton, the retaining flaps are folded through 180°, so that they lie against the inner side of their related holding flaps, and the retaining and holding flaps have interlocking means, through which the holding flaps act to hold the retaining flaps flexed inwardly out of the planes of their respective walls.

The patented carrier is of simple construction and the cans are held securely therein by the combination of retaining and holding flaps described. However, the inward folding of the holding flaps and the interlocking of the interlocking of the flaps to place the carrier in condition for loading requires the use of special machinery for high speed operation.

The present invention is, accordingly, directed to the provision of a can carrier, which includes the desirable combination of retaining and holding flaps disclosed in the patent but is of such construction that the flaps can be folded and placed in effective position as the carrier blank is being folded and glued on conventional gluing machines. In addition, the retaining flaps are cut from the top and bottom walls of the carrier and do not extend beyond the boundaries of the walls, so that the use of these flaps does not require additional paper board for the blank.

For a better understanding of the invention, reference may be made to the accompanying drawings, in which

Fig. 1 is a plan view of a blank for making one form of a carton embodying the invention;

Fig. 2 is a view in perspective of a partially erected carton made from the blank of Fig. 1;

Fig. 3 is a view in perspective of the fully erected carton shown in Fig. 2;

Fig. 4 is a view in perspective of another form of the carton of the invention;

Figs. 5, 6, and 7 are fragmentary perspective views with parts broken away, which show one form of the chime locking means of the invention at different stages in its completion;

Fig. 8 is a longitudinal sectional view through the completed chime lock of Fig. 5;

Fig. 9 is a plan view of the parts used in making another chime lock of the invention;

Fig. 10 is a view in perspective with parts broken away showing the completed chime lock made from the parts shown in Fig. 9;

Fig. 11 is a plan view of the parts used in another form of chime lock of the invention;

Figs. 12 and 13 are bottom perspective views showing different stages in the formation of the chime lock of the parts shown in Fig. 11; and

Fig. 14 is a longitudinal sectional view through the completed chime lock made of the parts shown in Fig. 11.

The blank 20 shown in Fig. 1 is employed in producing a carrier for holding six cans in two rows of three each with the cans in the two rows separated by a central partition. The carrier includes a handle and the cans are held in place by chime locks, which engage the chimes at the top and bottom of the end cans in each row.

The blank 20 comprises a pair of like side walls 21, 22 having edges connected along crease lines 23, 24, respectively, to the edges of top walls 25, 26. The opposite edges of the top walls are connected along crease lines 27, 28 to handle panels 29, 30 connected together along a crease line 31. The panel 29 has an opening 32, which registers with a flap 33 partially cut from panel 30 and connected to the panel along a crease line 34, the opening 32 being large enough to permit flap 33 to be pushed through it.

The outer edge of side wall 20 is connected along a crease line 35 to one edge of bottom wall 36 having its other edge connected along a crease line 37 to a central partition panel 38. The partition 38 is of the same width along crease line 37 as the bottom section 36 and side wall 21 but becomes narrower a short distance from crease line 37. At its end remote from the crease line, the partition is connected along a crease line 39 to a handle reinforcing panel 40 having an opening 41 adapted to register with flap 33 and large enough to permit the flap to pass therethrough.

The outer edge of side wall 22 is connected along a crease line 42 to one edge of a bottom wall 43, which is similar to bottom wall 36. The other edge of bottom wall 43 is connected along a crease line 44 to a glue flap 45.

Each of the top walls 25, 26 and the bottom walls 36, 43 is provided near its ends with chime locks for engaging the chimes of the end cans in the rows in the carrier and preventing the cans from being accidentally dislodged. The chime locks are identical and only one, such as the lock 46 in the end wall 36, will be described in detail.

The chime lock 46 comprises a retaining flap 47 partially cut from wall 36 and connected to the wall along a crease line 48, which extends transversely of the wall. The flap 47 extends inwardly from crease line 48 and is of increasing width toward its free end. The end edge 47a of the flap is formed by a cut and it has a shape determined by the shape of the cans with which the carrier is to be used. Thus, if the cans are rectangular in cross-section, the edge 47a is straight, but if the cans are cylindrical, the edge is curved, as shown, and its

curvature is approximately that of the inner surface of a chime of the can.

The chime lock is completed by a holding flap 49, which is partially cut from wall 36 and is connected thereto along a crease line. The flap 49 extends inwardly from its crease line and the crease line may be continuous, but is preferably formed in two parts 50a, 50b lying on opposite sides of the retaining flap and outward from its inmost point. In the chime lock shown, the sections 50a, 50b of the crease line start at the ends of the curved inner edge 47a of the retaining flap 47 and the cut forming the edge 47a also defines the edge of the holding flap 49 between the sections 50a, 50b of the crease line. The edge 47a of the retaining flap is thus convex and the outer edge of the holding flap lying between the sections 50a, 50b of its crease line is concave. When the inner edge of the retaining flap is straight, the crease line of the holding flap is preferably made in two sections extending outward from the side edges of the retaining flap at points lying outward from its inner end. In the chime lock shown, the flap 49 tapers in width toward its inner end and that end is of approximately the same length as the crease line 48.

In all forms of the new chime lock, the length of the holding flap measured between its crease line and the continuation of its free inner edge is such that, when the flap is folded through 180°, it overlaps the retaining flap 47. Preferably, the length l of the holding flap is not substantially the distance d between the crease line 48 of the retaining flap and the crease line 50a, 50b of the holding flap, so that when the holding flap is bent through 180°, it will overlie the retaining flap for substantially its entire length. When the length l equals distance d , the folding of the holding flap through 180° causes the outer end edge of flap 49 to coincide with crease line 48, as illustrated.

In converting the blank 20 into a carton, glue is applied to the inner faces of handle panels 29, 30 and to the outer face of glue flap 45 and the blank is folded on its crease lines to cause the handle panels 29, 30 to adhere to opposite faces of the handle reinforcing panel 40 and the glue flap to adhere to the face of the central partition 38 adjacent its crease line 37. The side walls 21, 22 then lie in the planes of their respective top walls 25, 26 and the bottom walls 36, 43 lie face to face, so that the carton is fully collapsed. To erect the glued carton from its collapsed condition, force is applied to the crease line 31 at the upper end of the handle and the crease lines 35 and 42 at the lower ends of the side walls 21, 22. As a result, the top walls 25, 26 are brought to the horizontal position as are also the bottom walls 36, 43. The carton is now made up of two sleeves 51, 52 of rectangular cross-section having a common side wall formed by the central partition 38 and outer side walls 21, 22. Each sleeve also has top and bottom walls connecting the side walls.

In order to place the chime locks in effective condition, the retaining flap 47 of each lock is bent out of the plane of its wall into the interior of the carton through an angle of about 90° and to the position illustrated in Fig. 6. While the retaining flap is in this position, the holding flap 49 is folded inward through an angle of 180° until it lies against the inner surface of the wall. The retaining flap is then folded back toward its initial position and until it engages the inner surface of the holding flap. As the overall width of the holding flap is greater than the greatest width of the retaining flap, the bending of the holding flap through 180° as described causes it to bear against the inner surface of the wall at opposite sides of the opening left by the folding of the retaining flap out of the plane of the wall. When the retaining flap is bent back to engage the inner surface of the holding flap, the retaining flap is kept out of the plane of the wall by the thickness of the holding flap 75

lying between the outer surface of the retaining flap and the inner surface of the wall. As a result, the inner edge 47a of the retaining flap is always held below the inner surface of the end wall and, when a can is inserted into the carton, the chime of the can flexes the retaining flap outward and, when released, the flap springs into the recess at the end of the can within the chime. The dimensions of the carton are such that each sleeve will hold a row of cans with the inner surfaces of the chimes of the end cans engaged by the ends of the retaining flaps. As these flaps are continuously held below the tops of the chimes by the holding flaps, the cans are held firmly in place by the retaining flaps and cannot be accidentally dislodged.

The form of the new carton shown in Fig. 4 is a single sleeve 53 made up of side walls 54, 55 connected by a bottom wall 56 integral with the side walls. The side walls are also connected by a top wall 57, which is integral with wall 55 and has a glue flap 58 secured to wall 54. The top and bottom walls are provided with chime locks 59 near opposite ends thereof and each lock may be similar to lock 46.

In the chime lock 46, the retaining flap 47 has a single continuous crease line 48 and, when the holding flap 49 is bent through 180°, it engages the inner surface of the carton wall only at the sides of the opening left by the folding of the retaining flap out of the plane of the wall. In the modified chime lock 60 shown in Fig. 9, the retaining flap 61 is connected to the end wall 62 along a crease line in two parts 63a, 63b and the adjacent ends of the parts of the crease line are connected by a curved cut forming a tab 64, which extends inward toward the median plane of the carton. The length l of the holding flap 65 approximates the distance d between the crease line 63a, 63b of the retaining flap and the crease line 66a, 66b of the holding flap. Accordingly, when the retaining flap is folded out of the plane of the wall 62 and the holding flap is folded through 180° to lie against the inner surface of the wall, the central part of the holding flap lies against the inner surface of the tab 64. When the retaining flap is then folded to lie against the inner surface of the holding flap, the tab 64 prevents the central parts of the retaining and holding flaps from bulging upwardly and thus avoids the possibility of the retaining flap becoming disengaged from the can chime.

The chime lock 67 shown in Fig. 11 is generally similar to that shown in Fig. 9 and includes a retaining flap 68 connected to the wall 69 along spaced crease lines 68a, 68b to leave a central tab 70, and a holding flap 71 connected to the wall along spaced crease lines 71a, 71b extending outwardly from the lateral edges of the retaining flap. The length l of the retaining flap 71 is slightly greater than the distance d between the crease lines of the holding and retaining flaps and, as a consequence, when the retaining flap is folded out of the plane of wall 69 and the holding flap 71 is folded through 180° to lie against the inner surface of the tab 70, the free end edge 71c of the holding flap lies outward a slight distance beyond the crease lines 68a, 68b connecting the retaining flap to the wall. The folding of the retaining flap 68 back toward the plane of the wall then causes the holding flap to buckle and bulge inward slightly and this stiffens the flap and causes it to hold the retaining flap more securely with the free edge of the retaining flap lying spaced inwardly from the inner surface of the wall. In order to facilitate the buckling of the wall 71, it may be formed with a transverse fold line 71d, as shown.

The folding of the retaining and holding flaps as described to place the chime locks in operative position is preferably done in two stages with the holding flaps folded against the inner surfaces of their walls at the time the carton blank is glued. The holding flaps can be held in such folded condition by gluing and, when the carton 75 is to be filled on a loading machine, the insertion of the

cans into the carton causes the retaining flaps to be swung against the holding flaps and into effective position.

I claim:

1. A carton for holding a row of cans having chimes at at least one end, which comprises a sleeve open at its ends and formed of a pair of like side walls and top and bottom walls connecting the top and bottom edges, respectively, of the side walls, a retaining flap attached to at least one connecting wall near one end thereof along a fold line extending transverse to the wall, the flap lying inward from the fold line and being bent along the fold line out of the plane of said wall into the interior of the sleeve, and a holding flap attached to said wall along a fold line parallel to and inward from the retaining flap fold line, the holding flap being folded through 180° along its fold line and lying between the under surface of said wall and the top of the retaining flap. 15

2. The carton of claim 1, in which the holding flap is connected to the wall along a fold line in two parts, which lie on opposite sides of the retaining flap between the free end and the fold line of the retaining flap, and a cut in said wall defines the end edge of the retaining flap and the outer edge of the holding flap between the two parts of its fold line. 20

3. The carton of claim 2, in which the cut has a 25

curvature approximating that of the chime of a can and the end edge of the retaining flap is convex.

4. The carton of claim 1, in which the fold line of the retaining flap is in two spaced parts connected by a 5 cut defining a tab and the free end of the holding flap lies beneath the tab.

5. The carton of claim 1, in which the length of the holding flap is greater than the distance between the fold lines of the holding and retaining flaps and the holding flap is transversely flexed.

6. The carton of claim 1, in which the retaining and holding flaps are duplicated near opposite ends of the wall.
